US00D776819S

(12) **United States Design Patent** (10) **Patent No.:** **US D776,819 S**
(45) **Date of Patent:** **** Jan. 17, 2017**

(54) **COMBINED MODULAR LASER DISPLAY SCREEN AND BASE**

(75) Inventors: **Alexander Vybornov**, Quincy, MA (US); **Felix Feldchtein**, Framingham, MA (US); **Paul Dunleavy**, Epping, NH (US); **Gregory Altshuler**, Lincoln, MA (US); **James Varney**, Maynard, MA (US); **Bryan Hotaling**, Harvard, MA (US); **John MacNeill**, Acton, MA (US); **Scott Leclerc**, Ashby, MA (US)

(73) Assignee: **Laser Abrasive Technologies, LLC**, Walpole, MA (US)

(**) Term: **14 Years**

(21) Appl. No.: **29/416,242**

(22) Filed: **Mar. 20, 2012**

(51) LOC (10) Cl. **24-03**

(52) U.S. Cl.

USPC **D24/160**

(57) **CLAIM**

The ornamental design for a combined modular laser display screen and base, as shown and described.

DESCRIPTION

FIG. 1 is a front view of a combined modular laser display screen and base embodying our new design;

FIG. 2 is a back view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.

The broken lines in the drawings represent unclaimed environmental subject matter and form no part of the claim.
